DRIP PAN FOR WATER COOLERS

Richard C. Wolfe, Los Angeles, Calif., assignor to California Consolidated Water Company, Los Angeles, Calif., a corporation of Delaware

Application April 19, 1932, Serial No. 606,113

6 Claims.

This invention relates to water coolers and dispensers and particularly to that type of portable dispenser in which the contents are cooled by evaporation from the outer surface of a wetted container and in which a drip pan or receptacle for waste and/or cooling water may be required.

These water coolers are provided with drip pans for two and in some cases three purposes. The first purpose is to receive waste water when a greater quantity is drawn from the faucet of the cooler than is consumed. The second is to receive any drip from the porous container, when such is used to cool the water by evaporation.

The third purpose and the one to which the improved drip pan of this invention is particularly directed is for holding a supply of water which is utilized to wet a porous or absorbent sleeve which may surround an impervious cooling chamber. Such an apparatus is disclosed in my copending application Serial No. 552,313, filed July 22, 1931, upon which Patent No. 1,913,866 issued June 13, 1933.

This type of cooler, as mentioned above, does not use the conventional porous or permeable container or "olla", but is provided with an impervious jar into which the water supply bottle is inverted and from which the water is withdrawn through the usual faucet. The impervious cooling vessel is preferably enclosed by a cylinder or guard which is adapted to shield it against radiant heat from surrounding objects and to insure a continuous flow of air for evaporation by the convection currents set up by such cooling.

The porous sleeve which surrounds the jar is received at its lower end into a pan of water which wets its external surface by capillary action, and this invention relates to improved supporting and retaining means for this pan.

The usual drip pans provided for such coolers are received into slots or rest upon projections extending inwardly from the frame supporting the body of the cooler. These pans are usually provided with a small side extension or catch basin which normally projects outward immediately below the faucet to receive the overflow or drip from a glass being filled or from the faucet. This catch basin is also utilized as a receiver for waste water.

It is sometimes convenient to fill a receptacle which is of such height that it will not fit into the space between the faucet and the catch basin previously mentioned. To provide for such contingencies the entire drip pan is so mounted that it may be rotated or rather oscillated approximately 20° so that the catch basin may be moved out from beneath the faucet and a tall receptacle, such as a pitcher, may be filled therefrom.

A further requirement of the drip pan, especially in the case of the cooler which utilizes

1,986,992

the above and other means for holding the water in the cooler, is that it must be easily removed and replaced.

It is an object of this invention to provide a drip pan which may be easily removed and replaced.

It is another object of this invention to provide a drip pan which may be easily removed and replaced.

It is another object of this invention to provide a drip pan which may be easily removed and replaced.

It is another object of this invention to provide a drip pan which may be easily removed and replaced.

It is another object of this invention to provide a drip pan which may be easily removed and replaced.

It is another object of this invention to provide a drip pan which may be easily removed and replaced.

It is another object of this invention to provide a drip pan which may be easily removed and replaced.

It is another object of this invention to provide a drip pan which may be easily removed and replaced.

It is another object of this invention to provide a drip pan which may be easily removed and replaced.

It is another object of this invention to provide a drip pan which may be easily removed and replaced.

It is another object of this invention to provide a drip pan which may be easily removed and replaced.

It is another object of this invention to provide a drip pan which may be easily removed and replaced.

It is another object of this invention to provide a drip pan which may be easily removed and replaced.

It is another object of this invention to provide a drip pan which may be easily removed and replaced.

It is another object of this invention to provide a drip pan which may be easily removed and replaced.

It is another object of this invention to provide a drip pan which may be easily removed and replaced.

It is another object of this invention to provide a drip pan which may be easily removed and replaced.

It is another object of this invention to provide a drip pan which may be easily removed and replaced.

guard or shield which surrounds the water container.

Referring to Figure 1, the numeral 10 represents a drip pan constructed according to this invention. The three legs or supports for the conventional water cooler are represented by numerals 11, 12 and 13 respectively, while the brackets attached to these legs and on which the pan normally rests are represented by 14.

10 In its normal position, when it is supported by brackets 14, and as shown in Figure 6, the catch basin 15 of pan 10 lies midway between legs 11 and 13, so that these brackets are beneath the outwardly extending flange 16 of the pan 10. 15 This position is represented in Figure 1 by the line OA. A small projection 17 (Figure 3) may be placed on the lower edge of the flange 16 to insure that the catch basin is registered in its proper relation with the faucet of the cooler (not shown). Under these conditions the pan 10 and catch basin 15 may be rotated approximately 20° to the left or in a clockwise direction from line OA, on which the faucet lies, in order that a receptacle which is too high to be received between the faucet of the cooler (not shown), and the top of the catch basin, may be filled. Pan 10 is prevented from turning any farther in this direction by the edge of catch basin 15 striking against leg 13 (Figure 1). Pan 10 and catch basin 15 may also be rotated approximately 20° to the right or in a counter-clockwise direction from line OA whereupon it will be arrested by the downward projections or lugs 18, on flange 16, illustrated in Figures 2, 3 and 4, for a purpose 30 which will be explained below.

The outwardly extending flange 16 of pan 10 is provided with three notches 19, as indicated in Figure 1, which are spaced at the same intervals as legs 11, 12 and 13 of the cooler support. These 40 are so related to the diameter of the flange of the drip pan and to the brackets 14, on the frame of the cooler support that the pan will be free to drop vertically downward when notches 19 coincide or register with these brackets as illustrated in Figure 1. It is to prevent the accidental dropping of pan 10 that the downward projections 18 are fitted to the rim 16 of the pan.

When it is intended, however, that the pan shall be removed, the catch basin 15 may be rotated 50 approximately 20° to the right or in a counter-clockwise direction and then lifted so that projections 18 will pass over brackets 14. It may then be rotated in the same direction (counter-clockwise) until notches 19 coincide or register 55 with these brackets, allowing the pan to be dropped vertically downward and removed from between the legs 11, 12 and 13 of the cooler frame, without danger of tipping. Downwardly extending lugs 20 may be added on the opposite sides of notches 19 from lugs 18 to insure accurate alignment of these notches with the brackets by preventing over-travel of the pan 10. The pan 10 obviously cannot be removed from the frame by lifting it upwardly because of the presence of the 60 water cooler structure, illustrated in part in Figure 6 by shield 25.

Referring now to Figure 5, the brackets 14 may be constructed as there detailed. The bracket itself may be made from a strip of metal bent to 70 provide a horizontal ledge 21 which is adapted to receive the horizontal flange 16 of the pan 10. The vertical upward extension 22 may be propor-

tioned to prevent transverse sliding of the flange 16 of the pan 10 when it is in its normal position. The bracket member 14 may be secured to the leg 13 by means of machine screws 23 and nuts 24 which pass through drilled holes in both the leg 13 and the bracket member.

It will be seen from this description that a drip pan, constructed according to this invention, will have advantages over those previously used in stability during normal operation and in ease 10 of removal and replacement when such is desired. It is also especially suited for use with the porous sleeve cooler construction outlined above, as it is adapted to be lowered vertically when being 15 installed, thereby leaving the lower end of the sleeve undisturbed.

Although a specific construction embodying this invention has been described and illustrated, it is to be understood that the invention is not 20 limited to that specific device, and all such modifications and changes as come within the scope of the appended claims are embraced thereby.

I claim:

1. In combination with a water cooler having 25 supporting legs, brackets on said legs, a drip pan adapted to fit between said brackets and supported by an annularly extending rim resting on said brackets, said drip pan being capable of limited rotation between said brackets, notches 30 in said rim adapted to register with said brackets upon rotation of said drip pan and stop members on said rim extending downward adjacent said notches.

2. In combination, a water cooler frame, a drip 35 pan within said frame, a flanged rim extending outwardly from said drip pan, spaced notches in said rim, spaced supports on said frame to engage said rim and permit removal of said pan when said pan is rotated to register said notches 40 with said supports.

3. In combination, a water cooler frame, spaced 45 brackets in said frame, and a drip pan provided with a flange and capable of limited rotation in said frame, spaced notches in said flange, said flange provided with a stop adjacent one of said notches to limit the rotation of said pan.

4. In combination, a water cooler frame provided with a shield, spaced supports in said frame below said shield, and a drip pan provided with 50 means to engage said supports upon partial rotation of said pan and without tipping the latter from a horizontal position, said shield acting to prevent a vertically upward removal of said drip pan from said frame.

5. In combination, a water cooler frame provided with a shield, spaced supports in said frame below said shield, a drip pan provided with means to engage said supports upon partial rotation of said pan and without tipping the latter from a 60 horizontal position, and stop means to limit the rotation of said pan, said shield acting to prevent a vertically upward removal of said drip pan from said frame.

6. In combination, a water cooler frame having 65 a shield at its upper end, spaced support means in said frame below said shield, and a drip pan provided with means adapted selectively to engage said support means to retain said pan within said frame, or to permit said pan to be withdrawn vertically downward therefrom.

RICHARD C. WOLFE.
